UNITED STATES PATENT OFFICE.

WALTER B. HOYT, OF ELMHURST, NEW YORK.

DESIGN FOR A GAS CHECK AND REGULATOR.

SPECIFICATION forming part of Design No. 28,185, dated January 18, 1898.

Application filed December 11, 1897. Serial No. 661,568. Term of patent 3½ years.

To all whom it may concern:

Be it known that I, WALTER B. HOYT, a citizen of the United States, residing at Elmhurst, Queens county, New York, have invented a certain new and original Design for a Gas Check and Regulator, of which the following is a full, clear, and exact description.

My invention relates to a new and original design for a gas check and regulator, of which the following is a specification.

Referring to the accompanying drawings, Figure 1 is a perspective view of a gas check and regulator embodying my new design. Fig. 2 is a view of the underside of the check 15 shown in Fig. 1.

As shown in the drawings, the leading or material feature of my design comprises a cylindrical body A, flared outwardly toward its upper end to form a cylindrical enlargement

B, which is again flared outwardly near the 20 extreme upper end of the check to form a flat circular ring C of slightly greater diameter. Within the concaved space at the upper portion of the check are lines crossing one another and an opening approximately in the 25 center, through which is visible an upwardly-directed extension.

Looking at the device from the under side, as illustrated in Fig. 2, the lower end of the check is shown as concaved, as at D, with a central bull's-eye within said concaved portion. 30

What I claim is—

A design for a gas check and regulator, as herein shown and described.

WALTER B. HOYT.
